DESIGN FOR A FINGER RING OR ARTICLE OF SIMILAR NATURE

Edward J. Gross, New York, N. Y., assignor to Benjamin & Edward J. Gross Co. Inc., New York, N. Y.

Application January 30, 1935, Serial No. 55,150

Term of patent 3½ years

To all whom it may concern:

Be it known that I, Edward J. Gross, a citizen of the United States, residing at New York, in the county and State of New York, have invented a new, original, and ornamental Design for a Finger Ring or Article of Similar Nature, of which the following is a specification, reference being had to the accompanying drawing, forming a part thereof.

Fig. 2 is a top plan view of the ring in flat arrangement, the portions shown in dotted lines being mere repeats of those shown in full outline.

I claim:

The ornamental design for a finger ring or article of similar nature, as shown and described. In testimony whereof I affix my signature.

EDWARD J. GROSS.
